UNITED STATES PATENT OFFICE

GEORGE ROBERTSON, OF BURLINGAME, CALIFORNIA

SEPARATOR

Application filed September 18, 1926. Serial No. 136,274.

My invention relates to that class of separators in which a difference in the gravity coefficient of the components of the aggregate is taken advantage of, under the influence of a fluid current, to effect a separation, by diverting said components to different destinations.

The invention, while applicable to many materials, is especially intended for the cleaning of grains, beans and the like, and particularly where, as in the case of coffee, a very appreciable volume of relatively lighter foreign substances is likely to be present, and which requires a special increase in the velocity of the fluid current and its thorough subjection thereto, in order to make the separation effective.

It is in regard to this feature of an increasing velocity of the fluid current and the effective exposure of the aggregate thereto that my invention appertains and in which it consists, as I shall now fully describe by reference to the accompanying drawings in which I show a preferred form of a separator embodying said invention, though it is to be understood that changes may be made in the form, structure and arrangement of the device without departing from the spirit of the invention as defined in the claims hereunto appended.

In the drawings,

Fig. 1 is a vertical longitudinal section of my separator.

Fig. 2 is a cross section on the line 2—2 of Fig. 1.

Fig. 3 is a sectional detail on the line 3—3 of Fig. 1.

Fig. 4 is a detail section showing a modification of the discharge end of the feed conduit.

1 is a casing housing or shell, through one end of which protrudes the combined separating and grading member comprising the aligned and communicating open ended cylinders 2 and 3, the former lying within the shell and being interiorly provided with the lifting and agitating vanes 4; and the latter passing through the shell end, and being divided into a plurality of screen zones of successively increasing mesh, each zone being as-

sociated with its individual receiving hopper 5 having controlling gates 6. Lying above the screen grader is a contact roll 7 to keep the meshes clear.

The combined separating and grading member has imparted to it a rotation upon its axis, and for this purpose the separating cylinder portion 2 is mounted peripherally upon rollers 8, and has motion transmitted to it through a peripheral gear 9, a pinion 10, a countershaft 11, a bevel gear 12 on the end of said shaft, and a bevel gear 13 on the shaft 14, by which power is led into the machine.

In the best disposition of the combined cylinders 2 and 3, a downward inclination is preferred as here shown, in order to facilitate the travel of the cleaned components towards their destinations, but this inclination is not wholly essential, as other means, well known in the art, may effect the necessary advance. Without the shell 1, at the inner end of the separating cylinder 2 is a cross-wall 15 forming in the left hand end of said shell a receiving chamber 16 for the separated lighter components, said chamber having an underlying hopper 17 with a screw conveyer 18 in its throat, at the end of which, as shown in Fig. 3, is a swinging discharge gate 19. The screw conveyer 18 is driven by a chain 20, indicated in Fig. 1 by dotted lines, from the inleading power shaft 14 to a sprocket 21 on the conveyer shaft, Fig. 3.

Within the receiving chamber 16 is a depending baffle 22 spaced from and opposing the inner end of the separating cylinder 2, the lower end of said baffle terminating above the hopper base 17 of said chamber, and being provided with a sliding gate 23, operated by a handled rod 24, for varying the depth of the space underlying said baffle.

Upon the top of the shell 1 is mounted a fan 25, the suction inlet 26 of which leads out of the upper portion of the chamber 16 beyond the baffle 22.

The course of the air current induced by the fan 25, as shown by the longer arrows, is from the outer open end of the grader cylinder 3, through said cylinder and through the separating cylinder 2, thence down under the baffle 22 and up to the fan.

The aggregate or material to be separated is fed into the machine from a hopper 27, which communicates with a feed conduit 28 leading down into the interior of the separating cylinder 2. Within the conduit 28 is the screw conveyer 29, which is driven by a chain 30 from a sprocket 31 on the conveyer shaft, to a sprocket 32 on the counter shaft 11.

The material to be separated, fills the feed conduit, so that no air passes through it. Said material, as shown by the shorter arrows, passes through the conduit and is delivered within the interior of the separating cylinder 2. In this cylinder it is picked up repeatedly by the vanes 4 and is spread out to expose it to the oppositely advancing air current. The lighter components are carried back by said current, as shown by the short arrows, and these components, emerging from the inner end of the cylinder 2, and meeting the baffle 22, drop down out of the current, into the hopper 17 and are discharged by the conveyer 18. The heavier particles of the aggregate pass on down and are graded in the cylinder 3 and suitably delivered.

As I have briefly intimated in stating hereinbefore the essential nature of my improvement, I have now to point out particularly in what manner and by what means the object sought is reached. It will be seen by reference to Fig. 1, that the feed conduit 28 projects into the separating cylinder 2 a considerable distance and that by reason of its diameter it occupies a certain annular space in said cylinder. The effect of this is to contract the interior cross-sectional space of said cylinder in the zone or region of its occupancy, and thus to increase the velocity of the air current. Manifestly such increased velocity is proportionate to the distance the feed conduit protrudes into the cylinder and to the diameter of said conduit relatively to the diameter of the cylinder.

Therefore, in the free front portion of the cylinder, the material is repeatedly carried around and spread out to meet the opposing air current, and the lighter particles are gradually and increasingly forced backwardly by the increased air velocity, thus tending to greater efficiency in separation, especially when relatively large quantities of worthless material are present.

The air suction of fan 25 is varied without varying the fan speed by operating dampers 25' and 26', one of which varies the area of suction inlet 26 and the other the area of an auxiliary air inlet in the suction pipe 26 above damper 26'.

When treating certain materials, particularly that which is quite heavy and compact, the conduit 28 may be provided within its length with a cutout area 32', affording a discharge opening orifice through which the

entire contents of the conduit passes into the cylinder 2.

To assure an air current of considerable velocity acting on the material within the cylinder 2, prior to its passing into the free front portion of the cylinder, a blind or closed extension 33 may be mounted on the conduit to close its end, it occupying an area in the cylinder corresponding to the conduit and extending for a distance beyond the normal length of the conduit.

1 claim:—

1. In combination with an apparatus for separating material having an inclined rotatable cylinder open at its upper end and having its lower end portion perforated and its upper end portion provided interiorly with vanes and provided with a blower for creating an air current through said cylinder in a direction opposite to the flow of the material to be treated, and including a baffle plate in spaced relation to the upper open end of the cylinder for diverting the direction of travel of the lighter components of the material blown from the cylinder, a feed conduit extending into the cylinder through its open upper end and terminating intermediate the ends of the cylinder, and a mechanical drive in said feed conduit, which closes the cross-sectional area thereof.

2. In combination with an apparatus for separating material having an inclined rotatable cylinder open at its upper end and having its lower end portion perforated and its upper end portion provided interiorly with vanes and provided with a blower for creating an air current through said cylinder in a direction opposite to the flow of the material to be treated, and including a baffle plate in spaced relation to the upper open end of the cylinder for diverting the direction of travel of the lighter components of the material blown from the cylinder, a feed conduit extending into the cylinder through its open upper end and terminating intermediate the ends of the cylinder, and a mechanical drive in said feed conduit, which closes the cross-sectional area thereof, said feed conduit being spaced from the cylinder walls so that air currents from the blower may pass therearound.

3. In combination with an apparatus for separating material having an inclined rotatable cylinder open at its upper end and having its lower end portion perforated and its upper end portion provided interiorly with vanes and provided with a blower for creating an air current through said cylinder in a direction opposite to the flow of the material to be treated, and including a baffle plate in spaced relation to the upper open end of the cylinder for diverting the direction of travel of the lighter components of the material blown from the cylinder, a feed conduit extending into the cylinder through its open upper end and terminating intermediate the ends of the cylinder, and a mechanical drive in said feed conduit, which closes the cross-sectional area thereof, said feed conduit being spaced from the cylinder walls so that air currents from the blower may pass therearound.

diate the ends of the cylinder, a mechanical drive in said feed conduit, which closes the cross-sectional area thereof, said feed conduit being spaced from the cylinder walls so that air currents from the blower may pass therearound, and means to vary the length of the feed conduit within the cylinder.

In testimony whereof I have signed my name to this specification.
